ALFRED E. MASKRNY, OF IRVINGTON, NEW JERSEY, ASSIGNOR, BY MESNE ASSIGNMENTS, TO INDUSTRIAL WELDED ALLOYS INC., OF NEWARK, NEW JERSEY, A CORPORATION OF DELAWARE

LINED TANK OR PRESSURE VESSEL

Application filed October 19, 1928. Serial No. 313,398.

This invention relates to the construction of tanks or pressure vessels which are intended for use in the treatment of materials under pressure and temperature. To sustain the high pressure employed in many chemical processes it is necessary that the walls of the tank or other vessel be of thick, strong material. Steel is best adapted for this purpose, but cannot be used for any process in which a chemical is involved which will have a corrosive action on the steel, or will be contaminated by contact with the steel.

Certain non-ferrous alloys are satisfactory so far as concerns non-corrosive and non-tainting action, but it is impractical, because of the expense involved, to construct the tank walls of such alloys and of the required thickness to sustain the pressures employed in the chemical treatment carried on in the tank.

So far as I am advised, no one has heretofore been able to make a steel tank with a corrosion resistant alloy lining which would prove satisfactory when the tank was subjected to wide variations in temperature. This was because of the marked difference in the coefficient of expansion of the main steel wall and the alloy lining. The lining would bulge at very high temperatures or would shrink away from the wall of the tank at low temperatures, and the lining of the peripheral wall would tear itself loose from the lining of the top or bottom when subjected to wide extremes of temperature.

The object of my invention is to provide a tank which may be made at low cost, which will have sufficient strength to withstand high pressure, and which will present an inner surface which will not be injuriously affected by the chemicals employed. I provide a steel tank which may be of any desired type of construction, and secure within it a liner of a corrosion resistant alloy or other non-corrosive material.

As the important feature of my invention I provide this liner with one or more helically arranged corrugations which will permit of both longitudinal and circumferential expansion or contraction of the liner

at the same rate as the expansion or contraction of the tank wall, so that the liner will be exteriorly supported to resist internal pressure, and will be free to move so that there is no liability of developing cracks or being torn loose at the ends or heads.

My invention may be carried out in various different forms depending on the purpose for which the tank is to be used, the range of pressures and temperatures to which it is to be subjected, and the character of the material to be treated therein.

In the accompanying drawing I have illustrated merely one embodiment as an example. In these drawings:

Fig. 1 is a side elevation of the upper portion of a tank, a part being broken away,

Fig. 2 is a transverse section on the line 2—2 of Fig. 1, and

Fig. 3 is an enlarged section similar to a portion of Fig. 2.

In the construction illustrated there is provided a peripheral wall 10 which may be a section of a large steel tube or may be built up from steel plates welded or riveted together. It is important that if welding or riveting be employed, the inner surface be smooth. In some cases where it is desirable to conserve the heat inside of the liner, a layer of brick, sand or similar insulating material is employed between the non-corrosive liner and the steel shell. In this case the liner expands and contracts against the brick or other insulating material instead of the steel shell, and the inner surface of such material should be smooth, although the inner surface of the steel shell obviously need not be. The tank is provided with top and bottom walls 11 which may be secured to the peripheral wall in any suitable manner to give the desired strength and fluid-tight connection. I have illustrated only the top of the tank and have shown the main walls of the tank somewhat conventionally, as these parts when considered alone are not new with me and may be varied within wide limits.

In carrying out my invention I provide the tank with a liner 12 of comparatively thin sheet material which will not contaminate or be corroded by the chemicals or other mate-

rials to be treated in the tank. This may be a chrome iron, or chrome steel, a chrome nickel steel, Monel metal, or other well-known alloy of the general stainless or non-corrosive type.

5 For some constructions I might use nickel or other metal in place of an alloy. The liner substantially follows the inner surface of the peripheral wall 10 of the tank, but is provided with a helical slit which will make at least one turn around the tank, although it may be of such pitch that it makes several turns. With the slit at an angle of about 45°, it will make one turn if the length of the tank be a little more than three times the 15 diameter. For shorter tanks the angle of the slit should be less, in order to make the complete turn.

At the slit there is inserted a corrugated strip 13 which runs lengthwise of the slit 20 and has its opposite edges welded to the body of the liner. This strip, by reason of its corrugations, may expand in a direction transversely to the length of the strip, and therefore in a direction having a longitudinal 25 and a circumferential component in respect to the tank. With this corrugated filler strip inserted in the liner and extending helically, the liner as a whole may expand or contract both lengthwise of the tank and circumferentially thereof, and may maintain firm contact with and be properly supported by the outer steel wall under all conditions of temperature and pressure. The ends of the liner 30 12 may be secured to liner sections 14 in the top and bottom of the tank in any suitable manner, and the end of the corrugated strip is likewise secured to the top and bottom liner sections. The corrugations may be flattened out at the end, or may be filled, or other suitable expedient employed for making a tight 35 joint.

There will be comparatively little strain on such joint because the body of the liner may expand and contract at will, and the ends of 45 the liner will remain firmly anchored to the ends of the tank. The number, height and character of the corrugations in the helical strip may vary depending upon the difference in the rate of coefficient of the outer wall 50 of the liner and the range of pressure and temperature to which the tank is to be subjected. I have illustrated only one such strip and provided it with only three corrugations, but a larger number of strips may be provided if desired, and the corrugations may 55 be of different form and different number, if desired.

I have referred to the corrugated portion as a strip, and have illustrated it as made of 60 a separate piece of metal welded in a slit in the body of the liner. It will of course be evident that it may be integral with the body of the liner and may be formed by rolling the helical corrugations directly in the cylindrical 65 cal liner.

Having thus described my invention, what I claim as new and desire to secure by Letters Patent is:

1. A tank or pressure vessel having a metallic liner including a helically arranged 70 expandible section.

2. A tank or pressure vessel having a liner of corrosion resistant alloy, provided with a helically arranged expansion strip.

3. A tank or pressure vessel having a steel wall and a metallic liner having a different coefficient of expansion, said liner being provided with a helical expansion strip permitting expansion of the liner both circumferentially and longitudinally.

4. A tank or pressure vessel having a metallic wall including a helically disposed corrugation permitting longitudinal and circumferential expansion.

5. A steel tank or pressure vessel having a liner of corrosion resistant alloy, said liner having a helically disposed strip making at least one turn around the wall of the tank, and provided with corrugations along the length of the strip permitting longitudinal and circumferential expansion of the liner.

6. A tank or pressure vessel having a metallic peripheral wall including a helically disposed corrugated expansion joint extending at approximately 45° to the axis of the tank.

7. A tank or pressure vessel having a metallic peripheral wall including a helically disposed corrugated expansion joint extending at approximately 45° to the axis of the tank, said expansion joint making at least one turn around the peripheral wall of the tank.

Signed at Irvington, in the county of Essex and State of New Jersey, this 13th day of October, A. D. 1928.

ALFRED E. MASKREY.
